DESIGN FOR A SUIT

Harry Redman, New York, N. Y.

Application May 29, 1946, Serial No. 130,220

Term of patent 3½ years

(Cl. D3—4)

To all whom it may concern:

Be it known that I, Harry Redman, a citizen of the United States of America, residing in New York city, county of New York, and State of New York, have invented a new, original, and ornamental Design for a Suit, of which the following is a specification, reference being had to the accompanying drawing, forming part thereof, wherein:

Figure 1 is a front view of a suit, showing my new design.

Figure 2 is a rear view of the suit shown in Figure 1.

I claim:

The ornamental design for a suit, substantially as shown.

HARRY REDMAN.
